191,968

BOAT HORN

Giacinto Guccioni, Corso Peschiera 160, Turin, Italy

Filed June 22, 1960, Ser. No. 61,097

Term of patent 14 years

(Cl. D72—1)

Fig. 1

Fig. 2

FIGURE 1 is a perspective view of a boat horn, showing my new design; and

FIGURE 2 is an enlarged elevation thereof as seen from the opposite side of FIGURE 1.

I claim:

The ornamental design for a boat horn, as shown.

References Cited in the file of this patent

UNITED STATES PATENTS

D. 40,186 Jones _____ July 27, 1909

OTHER REFERENCES

Perkins Marine Lamp & Hardware cat. No. 145, 1954, page 144, upper lefthand corner, FIG. 590, horn.